UNITED STATES PATENT OFFICE.

HANS K. LORENTZEN, OF NEW YORK, N. Y., ASSIGNOR TO DAVID IRWIN GARRETSON,
OF NEW YORK, N. Y.

APPARATUS FOR MANUFACTURING HORSESHOES.

1,078,296.

Specification of Letters Patent. Patented Nov. 11, 1913.

Application filed January 31, 1912. Serial No. 674,551.

To all whom it may concern:

Be it known that I, HANS K. LORENTZEN, a subject of the King of Denmark, and a resident of the city, county, and State of 5 New York, have invented a new and useful Apparatus for Manufacturing Horseshoes, of which the following is a specification.

In manufacturing horseshoes it is necessary to make several sizes of dies for different animals and in addition thereto it is necessary to make shoes of different sizes for the same animals; that is, shoes made for the fore feet of a horse are not suitable for the hind feet of the same animal because the 15 latter must be slightly narrower and longer than those for the fore feet. Heretofore it has been customary to manufacture various sizes for different animals and to separately manufacture the fore and hind shoes. When 20 the shoes are made by a drop forging process it is necessary to have a great many dies which are not only very costly in the first instance but their life is very short as it is almost impossible to manufacture more than 25 from five to ten thousand shoes from a single die before the latter becomes worn out.

The object of my present invention is to make it possible to form both fore and hind shoes from the same die or set of dies.

30 In addition thereto my object is to make it possible to carry in stock a smaller number of shoes.

My invention also relates to a novel die for converting the shoes, which die has a tapered opening through which horseshoes are adapted to be driven for the purpose of transforming fore shoes into hind shoes.

In the drawings forming a part of this application, Figure 1 is a plan view of the 40 die which forms a part of my invention. Fig. 2 is a cross section thereof taken on the line 2—2 of Fig. 1, and Fig. 3 is a longitudinal section taken on the line 3—3 of Fig. 1.

45 My improved die is suitable for use in a method which consists in manufacturing horseshoes of such shape and dimensions as will conform to the requirements for the fore feet of horses, preferably by any ordinary

drop forge method and afterward reforming or reshaping as many of the shoes as may be necessary to be used for hind shoes. For this purpose fore shoes of different sizes for different classes of horses may be formed according to the standard requirements and these shoes are somewhat wider and somewhat shorter than the shoes ordinarily required for the hind feet. That is to say, the fore shoes are usually curved outwardly at a point just beyond the toe calks to a point near the heels of the shoes in a somewhat larger arc than the hind shoe for the same animal; but the spread at the heel may be and preferably is, the same for both fore and hind shoes.

I first form a number of shoes of suitable size and dimensions for the fore feet and make the same of standard size, that is, I make shoes known as 1, 2, 3, 4, 5, etc., and then after producing all of the shoes in the 55 forging dies which produce shoes suitable for the fore feet I pass a number of these shoes through a tapered die for the purpose of reshaping the same to make them conform to the requirements for hind shoes. 60 This latter operation is very simple and inexpensive and may be performed after the 65 shoes are otherwise completely finished. This operation may be performed by the manufacturer previously to putting the 70 shoes on the market or it may be performed by the jobber or wholesaler according to the 75 proportion of fore and hind shoes required for his particular sales. That is to say, if a dealer has a thousand sets of shoes in stock 80 he is very apt to receive orders for a larger 85 percentage of fore shoes than hind shoes and it is possible, by keeping in stock only fore shoes, and by converting only such proportion of fore shoes into hind shoes as the sales 90 may require, to supply the ordinary demand from the smallest stock of shoes.

In the drawing forming a part of this application I have shown a tapered die. This die consists of a bed 1, adapted to be bolted 95 to any suitable support and extending upwardly from this bed I have arranged a rectangular flange consisting of end members

2 and 3, and side members 4 and 5, which serve to hold the several parts of the die in position. The bed 1 is provided with an opening 6, in line with the opening of the die, through which shoes are adapted to be driven. The die itself is provided with an opening 7, through which shoes are adapted to be driven. This opening at the top 8, where the shoe 9, is inserted is so shaped and proportioned as to conform to the contour of a shoe formed in the proportion and shape of a fore shoe. The side walls 10, 11, of the die preferably between the points 12 and 13, gradually taper inwardly from the top of the opening 7 to the bottom 15, thereof, at 14. This makes the bottom of the opening of slightly smaller width than the top. At the point 16, the wall of the die is made slightly longer than the heels 17, of the shoe at the time the latter is inserted at the top of the die in order to allow for the slight lengthening of the shoe as it is passed through the die.

I have provided extensions 18, which are so arranged in the die as to come between the heel portions 17, and the walls 19, of these extensions are preferably perpendicular so that as the shoe moves through the die the heel portions will be pressed against the block and will emerge from the die the same distance apart as when the shoe is first placed in the die. I have so constructed the die that it can be adjusted for different size shoes in order that one die may serve for all. For this purpose I have constructed a die in four separate pieces 20, 21, 22, and 23, and in order to adjust the die for shoes of different lengths I provide spacers 24, between the members 20, 23, and the members 22, 21. By inserting more or less of these spacers the length of the die may be suitably arranged for shoes of different length. In order to adjust the die for shoes of different widths I provide spacers 25, between the members 21, 20, and the members 22, 23, and by providing one or more of these spacers of suitable thickness between the die members the width of the opening of the die may be changed for shoes of different width. I have provided screws 26, which are threaded through the flange member 3, and are adapted to engage against the die members 20 and 21. I provide similar screws 27, threaded through the flange member 2, which engage against the die members 22, and 23, and together with the screws 26, coöperate to retain the die members in contact longitudinally of the die. I have provided screws 28, which are threaded through the flange member 5, in contact with the sides of the die members 20, 23. I have provided similar screws 29, which contact with the sides of the die members 21, 22. By tightening the screws 28 and 29 the die members are firmly held together in the lateral direction.

The shoes having been made to conform to the requirements for fore shoes any number or portion thereof may be converted into hind shoes by forcing them through this die. For this purpose the shoe is placed horizontally in the opening at the top thereof with the heels 17 in contact with the wall 19, and the shoe will conform to the curvature of the top of the opening 7. The shoe is then driven through the die by any suitable means and the inclination 10 of the side walls of the die will reduce the lateral dimensions of the shoe. At the same time the walls 19, will prevent the shoe from buckling by retaining the heels 17, in spaced relation and this action together with the action of the inclined walls 10 will cause the shoe to elongate as it passes through the die. The space 16 is to permit of this slight elongation. When the shoe passes through the die it will pass through the opening 6 in the bed plate. When the shoe has been driven through the die it will conform to the shape suitable for use as a hind shoe and will be in condition to be sold as such without further treatment. Regardless of the method by which the shoes are first formed this operation simplifies the manufacture of the shoes because all of the shoes of a given size may be first formed as fore shoes and afterward a portion thereof may be reshaped into hind shoes. It is particularly advantageous where shoes are made by a drop forging method.

Having described my invention, what I claim is;

1. A die having an opening through which a horse shoe is adapted to be passed, said opening being defined by slanting side walls for the purpose set forth, and a spacing block adapted to coöperate with the heel portions of the shoe for the purpose of preventing a buckling of the shoe while the latter is reduced in its lateral dimensions by the inclined walls.

2. A die for the purpose set forth comprising a plurality of separable die members, spacers for the said die members adapted to retain the die members in spaced relation, said die members having an opening for the passage therethrough of a horse shoe, said opening being shaped at one end to conform to the contour of a horse shoe and having inclined side walls for the purpose of reducing the lateral dimension of the shoe as the same is forced therethrough, and means for preventing a buckling of the shoe as it is forced through the die, and means for firmly holding the die members together.

3. A die for the purpose set forth, comprising a bed having a rectangular flange forming a die pocket, a die arranged in said pocket and consisting of members 20, 21, and 22, 23, said members 22 and 23 having separating blocks 18, separators for spacing said die members, one of which is adapted to sep-

arate the members 18, said die members having an opening for the passage therethrough of a horse shoe, the walls of said opening being inclined for the purpose set forth, said incline extending from points near the front of the shoe to points near the ends thereof, and of gradual increasing extent between said points.

Signed at the city, county and State of New York, this 26th day of January, 1912. 10

HANS K. LORENTZEN.
